UNITED STATES PATENT OFFICE.

HERBERT H. HEWITT, OF BUFFALO, NEW YORK.

CASTING-MACHINE.

1,158,921.

Specification of Letters Patent.

Patented Nov. 2, 1915.

Application filed February 13, 1912. Serial No. 677,356.

To all whom it may concern:

Be it known that I, HERBERT H. HEWITT, a citizen of the United States, and a resident of Buffalo, county of Erie, and State of New York, have invented certain new and useful Improvements in Casting-Machines, of which the following is a full, clear, and exact description.

The invention relates to casting machines and more particularly to machines for casting car truck side frames of the type set forth in an application for Letters Patent filed by me December 8, 1911, Serial No. 664,634.

In the car truck set forth in this application, the side frames are provided with central bearing openings by which they are swiveled to the transverse connecting members of the truck to rock in vertical planes.

The side frames are also provided with longitudinally extending bearing openings which rotatably receive studs on the journal boxes to permit the rocking movement of the latter in transverse planes. The present invention seeks to provide an improved machine for casting the side frames in which permanent metal cores are employed for forming the bearing openings and for providing the same with smooth surfaces which need not be subsequently machined.

The invention consists in the features of improvement hereinafter set forth, illustrated in the preferred form in the accompanying drawings and more particularly pointed out in the appended claims.

In the drawings, Figure 1 is a plan view of the improved machine. Fig. 2 is a longitudinal central section thereof taken on the line 2-2 of Fig. 3. Fig. 3 is a side elevation. Fig. 4 is a partial longitudinal section taken on the lines 4-4 of Figs. 1 and 2. Fig. 5 is a detail section on line 5-5 of Fig. 1 of the valve which controls one of the core operating motors. Fig. 6 is a vertical section taken on the lines 6-6 of Figs. 1 and 8. Fig. 7 is a detail cross section taken on the line 7-7 of Fig. 1. Fig. 8 is a detail sectional view taken on the line 8-8, Fig. 6. Fig. 9 is a detail cross section taken on the line 9-9 of Fig. 2.

The frame of the machine comprises a horizontal bed plate 10 which is rectangular in outline and which is provided with end extensions 11 that are secured to suitable supports 12. The upper surface of the rectangular bed plate 10 is raised somewhat

above that of the end extensions 11 and is adapted to sustain the mold. The under side of the bed plate 10 and of the extensions 11 are provided with strengthening ribs and the bed plate is centrally sustained upon a series of uprights 13 (see Figs. 3 and 8) which rise from the upper end of a vertically disposed cylinder 14. The fluid pressure cylinder 14, in the form shown, is arranged within a pit 15 in the foundation 16 and at its lower end is provided with a flange 17 through which extend a number of bolts 18 to secure the cylinder to the foundation.

The car truck side frame which is cast by the machine is diamond shape in outline and comprises a large central portion *a* and the opposite pairs of converging arms *b* which extend from the central portion and which are connected at their outer ends by hub-like parts *c*. The central portion is provided with projecting bosses *d* in line with the hubs *c* and the hubs and bosses *c* and *d* are provided with bearing openings for studs on the journal boxes. The central portion *a* of the truck is provided with a transverse bearing opening and this central portion and the arms *b* are formed of a central web having strengthening flanges at its inner and outer edges.

The side frame is cast in a two-part mold the parting line of which extends through the central longitudinal plane of the side frame. In the construction shown, a sand mold is employed which is formed within a flask comprising an upper section or cope 19 and a lower section or drag 20. The flask is preferably formed of cast metal and the meeting edges of the sections thereof are provided with outwardly projecting flanges 21. The flange of the lower section or drag is provided with upwardly projecting guide pins 22 which extend through openings in the flange of the upper section to center and guide the latter as it is placed on or removed from the lower section. Each section of the flask is provided with a series of transverse and longitudinal ribs 23 and 24 which aid in sustaining the mold formed in the flask, but which are cut away, as indicated in Figs. 6, 7 and 9, so that they do not extend to the cavity of the mold. Each section of the flask is also provided at its upper central portion with a circular rib 25 which is integral with the transverse and longitudinal ribs 23 and 24 and which is provided with a series of inwardly projecting radial lugs 26.

These lugs at the upper and lower portions of the flask are arranged to engage a vertically movable cylindrical, metal core 27 which is adapted to form the central bearing opening of the side frame. The core 27 extends through and is guided within a central flanged opening in the bed plate 10 and is connected to the upper end of a vertical piston rod 29. The piston rod extends 10 through a stuffing box 30 on the head 31 of the cylinder 14 and is connected to a piston 32 within the cylinder. The lower portion of the permanent core 27 is preferably larger than its upper portion, so that it is provided with a shoulder 27^a which forms the outer edge of the flange about the central bearing opening.

A supply pipe 34 having a cut-off valve 35 therein (see Fig. 3) is connected by the 20 casing of a four-way valve 36 to a pair of branch pipes 37 leading to opposite ends of the cylinder 14. The casing of the four-way valve 36 is provided with an exhaust port and the stem of the arm is provided 25 with a crank arm 38. By shifting the valve either end of the cylinder may be connected to the supply pipe 34 and the opposite end to the atmosphere. Air or other suitable fluid under pressure is supplied to the 30 pipe 34 and by shifting the valve 36, is admitted alternately to the opposite ends of the cylinder 14 to shift the piston 32 back and forth and advance and withdraw the core 27 which extends transversely through 35 the bed plate 10 and transversely through the sections of the mold which removably mounted upon the bed plate.

A pair of cylindrical metal cores 39 are 40 shiftable through the ends of the sectional flask and mold and are preferably guided through semi-cylindrical flanged parts 40 formed upon the upper and lower sections of the flask. These cores are provided with reduced cylindrical portions 39^a which form 45 the bearing openings in the ends *c* of the side frame and at their inner ends the cores are provided with still further reduced portions 39^b which form the bearing openings in the bosses *d*.

50 Means are provided for detachably coupling the cores 39 to the pistons 43 of a pair of fluid pressure cylinders 44 which are secured to the outer ends of the extensions 11 of the bed plate or frame. The rods 45 of the pistons 43 extend through suitable stuffing boxes 46 on the inner ends of the cylinders 44 and are detachably coupled to the outer ends of the cores 39. For this purpose the outer ends of the cores and the inner ends of the piston rods are provided 55 with enlarged heads 47 which are adapted to abut and be retained within cavities formed in the upper and lower sections 48 and 49 of a sliding coupling. The lower 60 sections 49 are guided upon raised surfaces

50 on the frame extensions 11 and the upper sections are connected to the lower sections by hinged pintles 51. The opposite ends of the upper and lower sections 48 and 49 of the coupling are connected by a bolt 52, the 70 head of which is arranged within a recess in the lower section 49 and engages a transverse pin 53 by which the bolt 52 is swiveled to the lower section. The bolt 52 is adapted to extend through a notch in the end of the upper section 48 of the coupling and a hand wheel 54 threaded upon the upper end of the bolt engages the upper section 48 and securely clamps it in position. By loosening the hand wheel or nut 54 the fastening bolt 52 may be swung outwardly and downwardly and the upper section 48 of the coupling swung upon its hinged pinte 51 to release the connected ends of the core 39 and piston rod 45.

35 Supply pipes 55 having cut-off valves 56 therein are connected by the casings of four-way valves 57 each to a pair of branch pipes 58 which lead to the opposite ends, respectively, of the cylinders 44. The casings of the four-way valves 57 (see Fig. 5) are provided with ports 59 open to the atmosphere and the stems of the valves are provided with crank arms 60. By shifting the valves either end of the cylinder may be 95 connected to the supply pipe and the opposite end to the atmosphere, so that the pistons can be operated to withdraw the cores.

90 The arms 60 on the four-way valves 57 and the arm 38 on the four-way valve 36 are all preferably connected to a common 100 controlling lever 61 which is pivotally mounted upon a stud 62 on one of the side edges of the bed plate 10. For this purpose a pair of links 63 are connected at their 105 outer ends to the arms 60 and at their inner ends are pivotally connected to the lever 61 by a bolt 64. The lever 61 is provided with a crank arm 65 and this crank arm is connected to the arm 38 of the valve 36 by a link 66. In the operation of the machine it is desirable to start the operation of the pistons 43 of the cylinders 44 to withdraw the cores 39 before the cylinder 14 is thrown 110 into operation to withdraw the core 27. For this purpose the link 66 is provided with a pin 67 in its upper end which extends through a transverse slot 68 (indicated by dotted lines in Fig. 3) in the arm 65.

115 In the operation of the machine, the sections of the flask and the cores 39 are removed from the machine and the sand mold is formed therein with the cores 39 in their innermost position. It should be noted that 120 two of the transverse flanges 23 of the upper and lower flask sections are arranged to engage the inner portion of the body of the core 39 (see Figs. 4 and 7) to hold it in proper central position. In forming the 125 130

sand mold, a core similar to the core 27 is temporarily placed in position. In the particular form shown, the side frame is provided with key openings which extend inwardly in the central bearing opening thereof and which key openings are intersected by bolt openings. These key and bolt openings are formed by sand cores 67..

When the sand mold is properly formed 10 in the flask sections, the temporary central core is removed and the mold sections with the cores 39 therein are placed upon the bed plate 10 of the machine. In placing the mold sections on the machine, the lever 61 15 is manipulated to shift the valves 57 of the cylinders 44 and advance the pistons 43 and piston rods 45 thereof. The cores 39 are then securely connected to the piston rods 45 by the coupling sections 48 and 49. In 20 this way, the mold sections are properly centered upon the machine. The controlling lever 61 is then further shifted to operate the valve 36 and move the piston 32 of the cylinder 14 upwardly so that the core 27 is 25 advanced into the mold. When the core 27 is in position it is engaged by the radial lugs 26 on the rings or ribs 25 of the upper and lower flask sections. The upper end of 30 the core is slightly smaller than its lower end so that the lugs 26 on the upper flask section are longer than those upon the lower section, as indicated in Fig. 4. These lugs serve to properly position the mold and the cavity thereof with reference to the core 27. 35 When the parts are in position, the mold cavity is filled with molten iron and the cores 27 and 39 serve to form smooth surfaces upon the several bearing openings of the side frame, so that these openings need 40 not be subsequently machined. The lever 61 or other suitable controlling means is operated to admit air to the inner ends of the cylinders 14 and 44 to withdraw the cores 27 and 39, before the surfaces formed by the 45 cores are unduly chilled. This can be quickly effected at the proper time in the preferred form of the machine shown by manipulating the lever 61. The lower flask section 20 is provided with a series of pins 50 68 (see Figs. 2 and 9). There are four of these pins in the form shown and they are arranged to project upwardly from the lower portion of the flask to the face of the mold cavity, so that they engage the web 55 of the side frame which is formed in the mold cavity. These pins serve to support the central portion of the side frame as the core 27 is withdrawn and thereby prevent the withdrawal of the core from distorting 60 the casting. The cores 39 are shifted slightly in advance of the core 27 which serves to hold the mold in position as the cores 39 are withdrawn.

It is obvious that numerous changes may 65 be made in the details set forth without de-

parture from the essentials of the invention as defined in the claims.

I claim as my invention:—

1. In a casting machine, the combination with the machine frame, of a sectional mold supported thereon, a reciprocating metal core arranged to extend transversely through the mold sections, a pair of opposed, reciprocating, metal cores arranged to extend longitudinally through the ends of the mold, 70 said mold having metal portions engaging said cores, and means for withdrawing said cores, substantially as described.

2. In a casting machine, the combination with the machine frame, of a sectional mold supported thereon, a reciprocating metal core arranged to extend transversely through the mold sections, a pair of opposed, reciprocating, metal cores arranged to extend longitudinally through the ends of the mold, 80 75 said mold having metal portions engaging said cores, and fluid pressure motors connected to said cores for withdrawing the same, substantially as described.

3. In a casting machine, the combination with the machine frame, of a sectional mold supported thereon, a reciprocating metal core arranged to extend transversely through the mold sections, a pair of opposed, reciprocating, metal cores arranged to extend 90 95 longitudinally through the ends of the mold, said mold having metal portions engaging said cores, fluid pressure motors having movable members directly connected to said cores, and a common control lever for said 100 motors, substantially as described.

4. In a casting machine, the combination with a frame, of a sectional mold supported in horizontal position on said frame, a vertically reciprocating, cylindrical, metal core 105, guided in said frame and arranged to extend transversely through said mold sections, a pair of opposite, cylindrical, horizontally reciprocating metal cores arranged to extend through the ends of said mold between the sections thereof, said mold having metal portions arranged to engage said cores, said cores being adapted to form bearing openings in the casting, and means for withdrawing said cores from the openings formed thereby, substantially as described.

5. In a casting machine, the combination with a frame, of a sectional mold supported in horizontal position on said frame, a vertically reciprocating, cylindrical, metal core guided in said frame and arranged to extend transversely through said mold sections, a pair of opposite, cylindrical, horizontally reciprocating metal cores arranged to extend through the ends of said mold between the sections thereof, said mold having metal portions arranged to engage said cores, said cores being adapted to form bearing openings in the casting, a number of fluid pres- 125 130

sure motors arranged in line with said cores and having movable members connected thereto, and valves controlling the operation of said motors, substantially as described.

5 6. In a casting machine, the combination with a frame, of a sectional mold supported in horizontal position on said frame, a vertically reciprocating, cylindrical, metal core guided in said frame and arranged to extend transversely through said mold sections, a pair of opposite, cylindrical, horizontally reciprocating metal cores arranged to extend through the ends of said mold between the sections thereof, said mold having metal portions arranged to engage said cores, said cores being adapted to form bearing openings in the casting, a number of fluid pressure motors arranged in line with said cores and having movable members directly connected thereto, valves controlling the operation of said motors, and a common shift lever connected to said valves, substantially as described.

25 7. In a casting machine, the combination with a horizontal bed plate, of a sectional mold removably mounted thereon, a metal core arranged to reciprocate through said bed plate and extend transversely through said mold sections, said mold having metal portions arranged to engage said core on opposite sides of the mold cavity, and a fluid pressure motor below said bed plate having a movable member connected to said core, said mold having means for sustaining the casting as said core is withdrawn therefrom, substantially as described.

30 8. In a casting machine, the combination with a horizontal bed plate, of a sectional mold removably mounted on said bed plate, a pair of opposed, horizontally reciprocating, metal cores extending through the ends of said mold, a pair of fluid pressure motors mounted upon the ends of said bed plate, and means for detachably coupling said cores to the movable members of said motors, substantially as described.

35 9. In a casting machine, the combination with a horizontal bed plate, of a sectional mold removably mounted on said bed plate, a vertically reciprocating metal core guided in an opening in said bed plate and arranged to extend transversely through said mold sections, each of said mold sections having circular metal portions arranged to engage said core, a pair of opposed, horizontally reciprocating, metal cores arranged to extend through the ends of said mold between the sections thereof, said sections having metal portions arranged to engage said horizontally reciprocating cores, and means for withdrawing said cores from the opening in the casting formed thereby, substantially as described.

40 10. In a casting machine, the combination with a horizontal bed plate, of a sectional

mold removably mounted on said bed plate, a vertically reciprocating metal core guided in an opening in said bed plate and arranged to extend transversely through said mold sections, each of said mold sections 70 having circular metal portions arranged to engage said core, a pair of opposed, horizontally reciprocating, metal cores arranged to extend through the ends of said mold between the sections thereof, said sections 75 having metal portions arranged to engage said horizontally reciprocating cores, a number of motor cylinders arranged in line with said cores and having pistons connected thereto, and means for controlling the flow 80 of motive fluid to and from said cylinders, substantially as described.

11. In a casting machine, the combination with a horizontal bed plate, of a sectional mold removably mounted on said bed plate, 85 a vertically reciprocating metal core guided in an opening in said bed plate and arranged to extend transversely through said mold sections, each of said mold sections having circular metal portions arranged to engage 90 said core, a pair of opposed, horizontally reciprocating, metal cores arranged to extend through the ends of said mold between the sections thereof, said sections having metal portions arranged to engage said horizontally reciprocating cores, a motor cylinder below said bed plate having a piston connected to said vertically reciprocating core, 95 a pair of motor cylinders mounted on the ends of said bed plate and having pistons 100 connected to said horizontally reciprocating cores, and a common shifter for controlling the flow of motive fluid to and from said cylinders, substantially as described.

12. In a casting machine, the combination with a horizontal bed plate, of a sectional mold removably mounted on said bed plate, 105 a vertically reciprocating metal core guided in an opening in said bed plate and arranged to extend transversely through said mold sections, each of said mold sections having circular metal portions arranged to engage said core, a pair of opposed, horizontally reciprocating, metal cores arranged to extend through the ends of said mold between the sections thereof, said sections having metal portions arranged to engage said horizontally reciprocating cores, a motor cylinder below said bed plate having a portion 110 connected to said vertically reciprocating core, a pair of motor cylinders mounted on the ends of said bed plate and having pistons therein, and couplings for detachably connecting said pistons to said horizontally reciprocating cores, substantially as described.

13. In a casting machine, the combination with a bed plate, of a sectional metal flask for sustaining a sand mold removably mounted on said bed plate, a vertically re- 130

ciprocating metal core extending through said bed plate and arranged to extend transversely through said flask, a pair of opposed, horizontally reciprocating, metal cores arranged to extend longitudinally through the ends of said flask between the sections thereof, said flask having guiding portions arranged to engage said cores, and means for withdrawing said cores from the openings formed thereby, substantially as described.

14. In a machine for casting car truck side frames, the combination with the machine frame, of a mold comprising upper and lower sections sustained in horizontal position on the frame, a vertically reciprocating cylindrical, metal core arranged to extend transversely through the mold sections to form a central bearing opening, said sections having circular metal guide portions arranged to engage said core on opposite sides of the mold cavity, and a fluid pressure motor for reciprocating said core, substantially as described.

15. In a machine for casting car truck side frames, the combination with the machine frame, of a mold comprising upper and lower sections sustained in horizontal position on said frame, a vertically recip-

rocating metal core arranged to extend through said upper and lower mold sections, a pair of opposed, horizontally reciprocating cores arranged to extend through the ends of said mold between said sections, the latter having metal guiding portions arranged to engage said cores, and fluid pressure motors having movable members connected to said cores.

16. In a machine for casting car truck side frames, the combination with the machine frame, of a mold comprising upper and lower sections sustained in horizontal position on said frame, a vertically reciprocating metal core arranged to extend through said upper and lower mold sections, a pair of opposed, horizontally reciprocating cores arranged to extend through the ends of said mold between said sections, the latter having metal guiding portions arranged to engage said cores, fluid pressure motors arranged in line with said cores and having movable members directly connected thereto, and a common controlling lever for said motors, substantially as described.
